R. J. COSSEBOOM,
BUTTER MOLD,
APPLICATION FILED MAY 13, 1915.

1,168,168.

Patented Jan. 11, 1916.

UNITED STATES PATENT OFFICE.

ROBERT J. COSSEBOOM, OF BUENA VISTA, COLORADO, ASSIGNOR OF ONE-FOURTH TO DANIEL C. SINDLINGER AND ONE-FOURTH TO CHARLES A. NILES, BOTH OF BUENA VISTA, COLORADO

BUTTER-MOLD.

1,168,168.

Specification of Letters Patent. Patented Jan. 11, 1916.

Application filed May 13, 1915. Serial No. 27,827.

To all whom it may concern:

Be it known that I, ROBERT J. COSSEBOOM, a citizen of the United States, and a resident of Buena Vista, in the county of Chaffee 5 and State of Colorado, have invented an Improvement in Butter-Molds, of which the following is a specification.

This invention relates to molding devices, and more particularly to a butter mold including means for forming a suitable impression or design on one of the surfaces of the print.

One of the objects of the invention is the provision of a mold consisting of hinged 15 sides and ends having pivoted clamps for retaining them in closed position, a press block being vertically movable between said sides and ends and detachably carried by an adjustable operating rod.

20 Another object is the provision of a molding plate, having any suitable design thereon, detachably carried by the press block whereby the same may be removed and replaced by another plate having a different design.

25 A still further object is to provide a mold of this character which is simple in construction thus reducing the cost of manufacturing to a minimum and which is effective in carrying out the purposes for which it is designed.

The inventive idea involved is capable of receiving a variety of mechanical expressions, one of which, for the purpose of illustrating the invention, is shown in the accompanying drawing, in which—

35 Figure 1 is a perspective view of the mold constructed in accordance with the invention. Fig. 2 is a transverse section thereof, and Fig. 3 is a bottom plan view of the molding plate used in connection with the invention. Fig. 4 is a fragmentary top plan view partly in section.

40 Referring more particularly to the accompanying drawing, in which like reference characters indicate similar parts, the numeral 5 indicates the bottom of the mold box having the sides 6 and the ends 7 connected thereto by hinges 8 whereby the same 45 may be unfolded outwardly in order to facilitate the removal of a print of butter therefrom. The sides are retained in closed position by means of oppositely disposed

clamping elements 9 preferably formed of angle metal and hinged at 10 to a cleat 11 55 secured to one end 7 of the mold box adjacent the top thereof. The clamping elements are adapted to embrace the sides 6 and end 7 opposite to the end to which said clamping elements are pivoted, said elements being provided with handles 12 which are adapted to be grasped in order to retain the sides and ends in closed positions.

50 A vertically arranged bracket 13 is secured to the end 7 of the box which has the clamping elements hinged thereto and extends above the top of said box and has a plurality of openings 14 therein. Each of these openings is adapted to receive the hooked end 15 of an operating lever 16 60 which extends longitudinally of the box. The operating rod has slidably mounted thereon a block supporting bracket 17 having a sleeve 18 for engagement with said rod and being provided at its lower end with laterally extending wings 19 to which is secured a press block 20. A molding plate 21 is provided with a suitable design or configuration on its bottom face and is provided on its longitudinal edges with angular 65 flanges 22 which are adapted to engage the longitudinal edges and upper face of the press block 20 whereby said plate is retained in engagement therewith. From this construction it will be apparent that said plate 70 may be easily slid from engagement with the block and replaced, if desired, by another plate having a different design thereon.

75 In practice, the hooked end 15 of the operating rod may be inserted in any one of the openings 14 in the bracket 13 depending upon the size of the print to be molded in the box. The bracket 17 is then adjusted along the operating rod until the plate 21 is in position to be inserted in the mold box 80 after which the operator depresses the free end of the operating rod and causes the plate to form the impression upon the print, after which the clamping elements 9 may be 85 swung open in order to permit the sides and ends to be moved outwardly to permit the removal of the print. In order to retain the handles in closed position, when the butter is being packed into the mold, a cleat 90 23 is secured to one side of the mold and has connected therewith one end of a chain 24,

the other end of which is provided with a ring 25 adapted to be slipped over said handles, as shown in Fig. 1.

I claim:

- 5 A molding device substantially as herein described, comprising a molding box whose sections may open outwardly, a clamp comprising a cross-bar extending along the outer side of one end of the box, side bars 10 hinged at one end to the ends of said cross bar and extending thence along the sides and opposite end of the box and projecting beyond the end of the box in the form of handle portions, an operating rod or lever 15 pivotally supported at the end of the box carrying the cross-bar of the clamp and

extending thence longitudinally over the box and beyond the opposite end thereof and over the projecting handle portions of the clamp and in such relation thereto that 20 said handle portions of the clamp may be held together by the hand of the operator, which is simultaneously employed in holding the handle end of the operating rod down in operative position, and a press 25 block carried by the operating rod and operating within the box, all substantially as and for the purpose set forth.

ROBERT J. COSSEBOOM.
